UNITED STATES PATENT OFFICE.

CARL G. ROLINE AND CHARLES NORRE, OF CHICAGO, ILLINOIS.

REAMER FOR ENGINE-CYLINDERS AND THE LIKE.

1,360,444.

Specification of Letters Patent. Patented Nov. 30, 1920.

Application filed August 1, 1919. Serial No. 314,639.

To all whom it may concern:

Be it known that we, CARL G. ROLINE and CHARLES NORRE, citizens of the United States residing at Chicago, in the county of Cook and State of Illinois, have invented certain new and useful Improvements in Reamers for Engine-Cylinders and the like, of which the following is a specification.

This invention relates to improvements in reamers, particularly adapted though not necessarily limited in its use for re-boring engine cylinders, and one of the objects of the invention is to provide an improved device of this character which is readily adapted for use in any cylinder that is provided with a removable cylinder head, whereby the cylinder may be re-bored without necessitating the removal of the crank shaft and while the engine is in position upon the chassis.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which;

Figure 1 is a vertical longitudinal sectional view of an improved device of this character constructed in accordance with the principles of this invention with parts broken away and showing the same in its initial position in the re-boring of a cylinder.

Fig. 2 is a detail sectional view taken on line 2—2, Fig. 1.

Fig. 3 is a detail sectional view taken on line 3—3, Fig. 1.

Fig. 4 is a view similar to Fig. 1 showing the parts in another position and the position which the parts will assume just at the time of automatically releasing one of the pilots.

Fig. 5 is a sectional view on line 5—5, Fig. 4.

Fig. 6 is a detail perspective view of one of the cutter blades.

Referring more particularly to the drawing, the numeral 10 designates a cylinder which is to be bored.

The invention consists primarily of a shaft 11 which in use assumes an upright position and the shaft is supported by means of a suitable bracket or support 12 anchored in any suitable manner to a part of the

cylinder casing or a fixed support. This support is provided with an opening 13 in which is arranged a bearing 14 pivotally mounted by means of the trunnions 15. 60 This bearing is provided with internal screw threads with which the threads 16 connected with the shaft 11 coöperate so that when the shaft is rotated by means of the handle 17, it will be given an advancing movement in 65 a direction longitudinally of the shaft. The shaft may be of any desired size and length but is of a comparatively small size with respect to the internal bore of the cylinder. Secured to the shaft at any point intermediate its ends so as to rotate therewith is a cutter head 18 having a plurality of recesses or seats 19 extending longitudinally thereof and opening through the periphery. The ends of the head 18 are preferably reduced as at 19—20 and the reduced portions are provided respectively with peripheral threads 21—22 to receive the nuts or collars 23—24. A plurality of cutter blades 25 are provided, one for each of the seats 19. The 80 bottom of the seats 19 are inclined as at 26 and the lower edge 27 of each of the cutters is correspondingly inclined. One extremity of the cutter is inclined backwardly as at 28 and the opposite end of the cutter is preferably cut away as at 29 to form a shoulder 30 which is also inclined backwardly in a direction toward the opposite end 28. The extremity 31 of the cutter is also inclined backwardly for a purpose to be hereinafter 85 set forth.

One of these cutters 25 is seated in each of the seats or openings 19 and are of a length that the ends 28—30 will terminate adjacent the inclined shoulders 32—33 of the cutter head and preferably project a slight distance beyond said ends. The nut or collar 23 is provided with a concave face 34 and is adapted to be adjusted forwardly upon the threads 21 in any suitable manner such as by means of an instrument inserted in recesses 35. When this collar 23 is adjusted the inclined wall or concave portion 24 will engage or overhang the inclined end 28 of the cutter and when the collar 24 is 100 adjusted its inclined face 36 will engage and overhang the inclined end 30 of the cutter. Thus it will be seen that when the nuts 23—24 are adjusted toward each other, they will clamp and hold the cutters in position. The cut away portion 29 of the cutter 25 is provided so as to permit the ex-

tremity 31 to extend over the collar 24. With this arrangement it is possible to permit the cutters to cut for the entire length of the cylinder and the collar will not form any obstruction. In order to vary the degree to which the cutting edge of the cutter projects beyond the cutter head, the inclined surface 26 of the cutter head and the inclined surface 27 of the cutter are provided. In order to accomplish this adjustment, the collar 23 is adjusted away from the end 28 of the cutter for any desired distance and by then adjusting the collar 24, it will be seen that the cutters will be moved along the inclined surface 26, which will cause them to project for the desired distance. After the adjustment has been obtained, the collar 23 is then adjusted in clamping relation against the ends 28 of the cutters.

In order to provide an accurate adjustment and an adjustment which can be produced by anyone, the face 36 of the collar 24 is provided with a plurality of openings 25 27 and the spring controlled pin 38 is provided to coöperate with these openings so that it is possible to obtain a micrometer adjustment of the cutters by anyone without necessitating the using of any other measuring implements. Obviously and if desired, an indicating gage may be provided around the periphery of the collar 24 to indicate the adjustment.

The cutter head thus constructed is secured to the shaft 11 for rotation therewith in any suitable manner such as by means of a fastening screw 39 adapted to enter a groove 40 extending longitudinally of the shaft 11. This securing means also permits the cutter head to be adjusted in a direction longitudinally of the shaft.

Surrounding the shaft 11 on one side of the cutter head 18 is a pilot element 41 which is preferably of an inverted frusto 45 conical shape having a recessed portion 42 opening through one face and a recess 43 communicating with the recess 42. This pilot is supported normally by means of the cutter head 18 and in order to permit the 50 parts to be assembled closely, the recesses 42-43 are provided so as to receive the end 19 of the cutter head and the collar 23 as shown more clearly in Fig. 1.

A second pilot element is provided to 55 coöperate with the pilot element 41 and embodies a body portion 44 through which the shaft 11 passes. Connected with the body portion are a series of anchor elements 45 which are adapted to be projected beyond 60 the periphery thereof. This pilot element 44 is adapted to be inserted into the other end of the cylinder 10 and when in position a member 46 having a wedge shaped portion 47 is adapted to be adjusted with respect 65 to the body 44 through the medium of the

threaded connection 48 so as to force the anchor elements 45 beyond the periphery of the body 44 and into engagement with the wall of the cylinder to temporarily anchor the pilot in position and thereby form a 70 guide for one end of the shaft 11.

In order to provide a means whereby the pilot 44 may be inserted into the cylinder in position to be anchored, by the insertion of the shaft 11, the pilot is detachably connected with the end of the shaft in any suitable manner such as by means of a yielding lock 49 which is adapted to enter a recess 50 in an extension 51 of the adjustable member 46. 80

In use, the head on the end of the cylinder that is to be bored is removed. The pilot 44 is then detachably connected with the end of the shaft 11 by inserting the end of the shaft into the pilot. The end of the shaft 85 with the pilot connected thereto is then inserted into the cylinder until the pilot 44 assumes a position just inside of the lower end of the cylinder. The parts are then held in this position and the member 46 is 90 adjusted with respect to the body of the pilot 44 by means of a suitable adjustment tool or wrench 52 detachably connected with the member 46 as shown in Fig. 1, so as to project the anchor elements 45 and cause them 95 to grip the wall of the cylinder. The cutter head 18 is then adjusted or positioned so that the inclined ends 31 of the cutters 25 will rest upon the upper edge of the cylinder. These inclined ends will center the 100 cutter head and when in position as shown in Fig. 1 the pilot 41 will be supported by the cutter head. The bracket or support 12 is then anchored, the pivoted bearing 14 permitting a proper positioning of the 105 bracket with respect to the shaft and the instrument will then be in position for operation. When the shaft 11 is rotated by the 110 handle 17 the feed screw 16 will advance the shaft longitudinally and the cutter head 18. 110

As the shaft is advanced the connection 49 between the shaft and the pilot 44 will yield and permit the shaft to be fed longitudinally through the pilot 44 while the pilot remains anchored. As the cutting advances the cutter head will advance and with it the shaft 11 until the cutter head assumes a position entirely within the cylinder. As the cutter head advances the pilot 41 will travel with it but when the pilot 41 engages the end of the cylinder, its advancing movement will be arrested while the cutter head continues to advance. In this position the pilot 44 will form a guide for the shaft at that end of the cylinder. 115

In order to automatically release the pilot 44 to permit the cylinder to be entirely bored throughout its entire length, there is provided on the cutter head suitable projections or pins 53, any number of which may be 120 125 130

provided, and similar pins or projections 54 are provided on the adjustable element 46 of the pilot 44. These pins or projections 53-54 are so located with respect to 5 each other that when they are brought into inter-engaging relation, a continued advancing movement of the cutter head will cause the inter-engaging pins 53-54 to interlock so that the element 46 of the pilot 44 will 10 be rotated with the cutter head 18 while the body of the pilot 44 remains still and this will adjust the element 46 in such a manner that the wedge shape portion 47 thereof will move out of engagement with the anchoring 15 elements 45 to permit them to recede, thereby unlocking or releasing the pilot 44 so that the latter will drop out of the end of the cylinder. When this pilot is thus removed, the cutter head 18 can be further 20 advanced to travel entirely through the end of the cylinder from which the anchor 44 has been released.

With this improved construction it will be manifest that any cylinder may be re-bored while the cylinder is in position and 25 without removing the cylinder from the chassis.

While the preferred form of the invention has been herein shown and described, many 30 changes may be made in the details of construction and in the combination and arrangement of the several parts without departing from the spirit of this invention.

What is claimed as new is:-

- 35 1. A cylinder reamer embodying a shaft, a cutter head connected with the shaft for rotation therewith, blades connected with the cutter head, a pilot loosely mounted upon the shaft for adjustment longitudinally of the shaft, means for rotating the 40 shaft and cutter head, means for imparting a longitudinal feeding movement to the shaft as it is rotated, a second pilot for the shaft, means for anchoring the last recited pilot, and means operating automatically to release the anchored pilot.
- 45 2. A cylinder reamer embodying a shaft, a cutter head connected with the shaft for rotation therewith, blades connected with the cutter head, a pilot loosely mounted upon the shaft for adjustment longitudinally of the shaft, means for rotating the shaft and cutter head, means for imparting a longitudinal feeding movement to the 50 shaft as it is rotated, a second pilot for the shaft, means for anchoring the last recited pilot, and means for automatically releasing the second recited pilot at a predetermined point in the advancement of the cutter head 55 with the shaft.
- 60 3. A cylinder reamer embodying a shaft, a cutter head connected with the shaft for rotation therewith, blades connected with the cutter head, a pilot loosely mounted upon the shaft for adjustment longitudinally 65 of the shaft, means for rotating the shaft and cutter head, means for imparting a longitudinal feeding movement to the shaft as it is rotated, a second pilot for the shaft, means for anchoring the last recited pilot, and means operating automatically to release the anchored pilot.
- 70 4. A cylinder reamer embodying a shaft, pilot elements through which the shaft has a free longitudinal movement, means for temporarily anchoring one of the said elements at one end of the cylinder, a cutter head carried by the shaft intermediate the pilots, 75 said cutter head being connected with the shaft for advancement and rotation therewith, blades carried by the cutter head, the other of said pilots being normally supported by the cutter head, said cutter head being movable away from the last recited pilot when the latter engages the end of the cylinder and is arrested in its forward movement longitudinally of the shaft, means for rotating the shaft, means for feeding the 80 shaft longitudinally, and means operating automatically to release the anchored pilot.
- 85 5. A cylinder reamer embodying a shaft, pilot elements through which the shaft has a free longitudinal movement, means for temporarily anchoring one of the said elements at one end of the cylinder, a cutter head carried by the shaft intermediate the pilots, 90 said cutter head being connected with the shaft for advancement and rotation therewith, blades carried by the cutter head, the other of said pilots being normally supported by the cutter head, said cutter head being movable away from the last recited pilot when the latter engages the end of the cylinder and is arrested in its forward movement longitudinally of the shaft, means for rotating the shaft, means for feeding the shaft longitudinally, and means operating automatically to release the anchored pilot.
- 95 6. A cylinder reamer embodying a shaft, pilot elements coöperating with the shaft for centering the shaft in the cylinder, said shaft having a free longitudinal movement through and a rotatable bearing in the pilot members, means for anchoring one of the pilot members, a cutter carried by the shaft intermediate the pilot members, a support, 100 a pivotally mounted bearing for the shaft and mounted upon the support, and a threaded connection between the shaft and bearing whereby the shaft will be fed longitudinally to advance the cutter head when 105 a rotary movement is given to the shaft.
- 110 7. A cylinder reamer embodying a shaft, pilot elements coöperating with the shaft, said shaft and pilots being adapted for free relative movements in directions longitudi- 115
- 120
- 125
- 130

1. A cylinder reamer embodying a shaft, a cutter fixed to the shaft intermediate the pilots, means for anchoring one of the pilots in one end of the cylinder, the other pilot being adapted to engage 5 the other end of the cylinder and to be arrested thereby in its advancing movement, a stationary support with which the shaft has a threaded connection whereby the shaft when rotated will be given a longitudinal movement to feed the cutter through 10 the cylinder, and means for yieldingly connecting the first recited pilot to the shaft, whereby the same may be placed in position to be anchored by the insertion of the shaft 15 into the cylinder.
2. A cylinder reamer embodying a shaft, pilot members for the shaft, a cutter fixed to the shaft intermediate the said pilot members, means releasably connecting one of 20 the pilots with the shaft, whereby the pilot may be positioned in the cylinder by the insertion of the shaft, means for anchoring the last recited pilot against movement, the other pilot being normally spaced from one 25 end of the cylinder by the cutter, and adapted to follow the cutter as the latter is advanced, the last recited pilot being adapted to engage and be arrested by one end of the cylinder while the advancement of the cutter, 30 continues, means for rotating the shaft, and means for imparting a longitudinal movement to the shaft as it is rotated whereby the advancement of the shaft will automatically release the anchored pilot.
3. A cylinder reamer embodying a shaft, means for advancing the shaft in a direction longitudinally thereof, pilot elements connected with the shaft for adjustment one with relation to the other in a direction 35 lengthwise of the shaft, a cutter connected with the shaft for rotation therewith and intermediate the pilots, one of said pilots embodying a body, anchoring elements carried by the body and adapted to be projected 40 therebeyond to engage the cylinder wall, an adjustable element carried by the body and

adapted to project the said anchoring elements, and means whereby the said cutter will automatically adjust the said adjustable elements to release the said pilot. 50

4. A cylinder reamer embodying a shaft, means for advancing the shaft in a direction longitudinally thereof, pilot elements connected with the shaft for adjustment one with relation to the other in a direction lengthwise of the shaft, a cutter connected with the shaft for rotation therewith and intermediate the pilots, one of said pilots embodying a body, anchoring elements carried by the body and adapted to be projected 55 therebeyond to engage the cylinder wall, an adjustable element carried by the body and adapted to project the said anchoring elements, and means whereby the said cutter will automatically adjust the said adjustable elements to release the said pilot, the last recited means embodying means carried by the said adjustable element and the said cutter and adapted to be brought into cooperative relation by the operation of the 60 said shaft.

5. A cylinder reamer embodying a shaft, means for advancing the shaft in a direction lengthwise thereof, pilot elements connected with the shaft for adjustment one 65 with relation to the other in a direction lengthwise of the shaft, a cutter connected with the shaft for rotation therewith and intermediate the pilots, one of said pilots embodying a body portion, anchoring elements carried by the body and adapted to be projected 70 therebeyond into engagement with the cylinder wall, means for thus projecting the said elements, and means operating automatically at a predetermined point in the 75 operation of the cutter for releasing the anchored pilot.

In testimony whereof we have signed our names to this specification, on this 29th day of July, A. D. 1919.

CARL G. ROLINE.
CHARLES NORRE.
